UNITED STATES PATENT OFFICE.

JAY EDWARD LEHMAN, OF CANTON, OHIO.

PLANER.

Application filed April 22, 1921. Serial No. 465,594.

To all whom it may concern:

Be it known that I, JAY E. LEHMAN, a citizen of the United States, residing at Canton, in the county of Stark and State of Ohio, have invented a new and useful Planer, of which the following is a specification.

This invention relates to planers and has for its objects the provision of a planer in which a driving motor is carried upon the upper end of the column, thus producing a separate unit having a self-contained drive; other objects being the provision of means whereby the belt, connecting the drive pulley of the motor with the drive mechanism of the planer, may be held taut at all times.

With these objects in view, the invention consists in the construction and arrangement of parts hereinafter described and illustrated in the accompanying drawing, it being understood that changes in the form and details of construction may be made without departing from the appended claims.

The invention thus set forth in general terms is illustrated in the accompanying drawings in which,

Figure 1 is a perspective view of a planer embodying the invention;

Fig. 2, a perspective view from the rear side of the planer; and

Fig. 3, a side elevation, partly in section, of the upper portion of the column and the motor showing the belt tightening means.

A practical embodiment of the invention is disclosed in the accompanying drawings, forming a part of this specification in which similar numerals of reference indicate corresponding parts throughout the several views.

In the planer shown in the accompanying drawing, the base is indicated generally at 1 and has slidably mounted thereon the reciprocating table 2 arranged to be reciprocated longitudinally upon said base by suitable mechanism, the work being clamped upon said table in the usual manner.

The column 3 is shown located upon the operator's side of the table in order that work which is considerably wider than the table may project beyond the opposite edge 50 of the table and thus not interfere with the operator, whose position is upon the side of the machine adjacent the column in proper position to control the different operating levers and wheels and the switch which controls the motor.

The arm 4 is mounted upon the column 3

and extended over the table 2 and arranged to be raised and lowered upon the column in the usual manner, the raising and lowering means being controlled by the shaft 5 which may be rotated by any suitable tool when it is desired to adjust the arm vertically upon the column.

The tool head 6 is mounted upon the arm 4 and arranged to be moved laterally thereon by means of the usual screw threaded shaft 7, this shaft having a squared extremity 8 to which a crank or similar tool may be applied for operating the cross feed.

The vertical feed of the tool is controlled through the shaft 9 which is also provided with a squared extremity 10 for the reception of a crank or the like. The usual gearing which is operated through the shaft 9, cooperates with the rack 11 to produce the vertical feed.

The mechanism for reciprocating the table is operatively connected to the pulley 12 and for the purpose of driving said pulley, a motor 13 is mounted upon the upper end of the column 3, the pulley 14 of said motor being connected to the pulley 12 by means of the belt 15.

As the belt 15 is suspended in a substantially vertical position between the pulleys 12 and 14, it is desirable that some means be provided for keeping the belt stretched tight between said pulleys and for this purpose the motor 13 is fixed upon the hinged plate 16 as by means of the screws 17, said plate being hinged along one side edge to the upper end of the column 3 as shown at 18. Adjusting screws 19 are threaded through the opposite edge portion of the plate 16 and engage the upper surface of the column 3.

If at any time the belt becomes loose, the slack may be immediately taken up by adjusting the screws 19 to swing the plate 16 upwardly upon its hinge, raising the pulley 14 of the motor, thus lengthening the distance between said pulley and the pulley 12, thus tightening the belt.

For the purpose of changing the speed of the table 2, suitable speed changing mechanism is provided within the base 1 and operated by the levers 20 and 21. Suitable mechanism for locking the table against movement is also provided and arranged to be controlled by the hand wheel 22.

From the above description it will be evi-

dent that a planer is provided having a self-contained driving mechanism by means of which the planer forms a separate unit which may be placed in any location and 5 operated without the necessity of attaching to a line shaft or other driving means. All of the controlling mechanism for operating the different parts of the planer, as well as the switch 24 which controls the motor, 10 are located in position to be easily accessible to the operator of the planer without the necessity of reaching over or walking around the planer.

The motor is mounted upon the top of 15 the column and the belt connecting the motor pulley to the drive pulley of the planer is located upon the side of the column away from the table, thus not interfering with the operation of the planer and a simple and efficient means is provided for preventing any slack in the belt and holding the same tight at all times.

I claim:—

1. In a planer comprising a base having 25 a reciprocating table thereon, and a vertical column provided at one side of the base, and a drive pulley connected to the driving mechanism of the table, a plate upon the column, a motor mounted upon 30 said plate, and adjusting screws for raising the plate to tighten said belt.

2. In a planer comprising a base having

a reciprocating table thereon and a vertical column provided at one side of the base, and a drive pulley connected to the driving 35 mechanism of the table, a motor mounted upon the upper end of the column, a belt connecting said motor to said drive pulley and means for raising said motor to tighten said belt.

3. In a planer comprising a base having a reciprocating table thereon and a vertical column provided at one side of the base, and a drive pulley connected to the driving 40 mechanism of the table, a motor hinged- 45 ly mounted upon the upper end of the column, a belt connecting said motor to said drive pulley and means for tilting the motor upon its hinge to tighten said belt.

4. In a planer comprising a base having 50 a reciprocating table thereon and a vertical column provided at one side of the base and a drive pulley connected to the driving mechanism of the table, a plate hinged at one edge to the outer end of the column, 55 a motor mounted upon said plate, a belt connecting said motor to said drive pulley, and adjusting screws located through the free edge portion of the plate for tightening said belt.

In testimony that I claim the above, I have hereunto subscribed my name.

JAY EDWARD LEHMAN.
